ELECTRICAL SPACE DISCHARGE TUBE

Bernard C. Gardner, Waltham, Mass., assignor to
Raytheon Manufacturing Company, Newton,
Mass., a corporation of Delaware

Application May 21, 1947, Serial No. 749,545

8 Claims. (Cl. 315—5)

1

This invention relates to electrical space discharge tubes, and more particularly to tubes of the velocity-modulated types known as klystrons and reflex klystrons. Such tubes utilize resonant cavities, and are capable of generating ultra-high-frequency oscillations.

It is desirable, in order to be able to cover a range of frequencies with a single tube of the above general character, to have some means for tuning or varying the resonant frequency of the klystron at will, thereby varying at will the fundamental frequency of oscillation.

An object of this invention is to devise a novel means for controllably tuning a cavity resonator.

Another object is to provide means for controllably tuning a klystron, said means effectuating a very rapid tuning of such klystron.

A further object is to devise a means for varying the resonant frequency of a klystron oscillator, which is quite simple and which requires no mechanical linkage, thereby eliminating the time lag and backlash inherent in such linkages.

A still further object is to devise a means, for thermally tuning the resonant cavity of a klystron, which has no appreciable thermal lag.

The foregoing and other objects of the invention will be best understood from the following description of some exemplifications thereof, reference being had to the accompanying drawings, wherein:

Fig. 1 is a partial longitudinal cross-section, on an enlarged scale, of a space discharge tube embodying the invention; and

Fig. 2 is a view, similar to Fig. 1, of a modification.

Referring now to Fig. 1, the numeral 1 generally designates a velocity-modulated electron discharge tube of the type known as a reflex klystron.

Said tube 1 includes a hermetically-sealed cavity resonator 2, to which are sealed upper and lower glass envelope portions 3 and 4, the interiors of parts 2, 3, and 4 communicating with each other and being sealed and exhausted in accordance with conventional practice to provide an evacuated enclosure.

Envelope portion 4 may be provided with a suitable press, not shown, at the bottom thereof, said press supporting, as by means of a stiff lead-in wire 5, a highly electron-emissive cathode 6 adapted to be heated, by means of a heater 7 supplied from a heating source 8, to a temperature suitable to bring about copious emission. Said cathode is surrounded by a focusing electrode 9, which is also supported from the lower press by a stiff lead-in wire 10. Wire 10 is connected to

2

the negative terminal of a battery 11, the positive terminal of which is connected to cathode lead 5, so that electrode 9 has a negative potential with respect to cathode 6.

- 5 The electron gun structure 6, 9 described above produces a compact stream of electrons which emerges through the end of electrode 9. This electron stream, whose axis coincides with the longitudinal axis of tube 1, is subjected to the 10 action of a pair of spaced electrodes 13 and 14 which are connected to the cavity resonator 2. Cavity resonator 2 is of generally hollow toroidal shape, as shown, is preferably made of relatively thick copper, and may be laminated, having a 15 lower portion 2a, a ring-shaped central portion 2b, and an upper portion 2c, portions 2a, 2b, and 2c being sealed together in the completed device. In order to abstract the high-frequency oscillatory 20 energy from tube 1, a window 15, made of a material transparent to such energy, is sealed into a corresponding opening provided through cavity resonator portion 2b at one side of tube 1; a hollow wave-guide 16 is coupled to said opening at said window.
- 25 Lower electrode 13 is substantially frusto-conical in shape, with its smaller diameter at the upper end thereof in Fig. 1, and is integral with lower portion 2a of the cavity resonator. This electrode has a solid metallic wall but is hollow.
- 30 The walls of the portion 2a are thinned toward the upper end of the electrode 13, so that at said upper end the said walls are extremely thin. The top end of the cone is cut off, so that said electrode has an axial opening extending entirely 35 therethrough at its upper end; electrons can therefore travel through said electrode.

Cavity resonator portion 2c has an integral, substantially vertical cylindrical wall 17, the axis of which coincides with the longitudinal axis of 40 tube 1. Electrode 14 is a very thin-walled shallow substantially cup-shaped element, the cylindrical wall of which is rigidly secured, as by brazing, for example, to the outer surface of cylindrical wall 17 of cavity resonator portion 2c. The center of the disk wall of the cup is depressed to 45 form a very shallow cone frustum, and an axial opening is cut through said wall, this opening being of the same diameter as the axial opening in electrode 13, and is also for the purpose of allowing the passage of electrons through said electrode. Electrode 14 is made of a metal or 50 metallic alloy which has a low specific heat conductivity and a substantial thermal coefficient of expansion, such as a high-expansion type of 55 stainless steel. If desired, electrode 14 may be

copper-plated to increase its radio-frequency conductivity, but this plating does not appreciably interfere with its heat-expansion characteristics.

The openings in electrodes 13 and 14 are aligned with the center of the electron gun, and the electrodes are axially spaced to provide a gap 18 between the same, said gap having a length a , so that a linear axial electron path is provided between said electrodes, this linear path extending from cathode 6 through electrodes 13 and 14 to a point above the upper electrode 14. Due to the fact that electrode 14 has a frusto-conical shape, it forms an angle different from 90° with the direction of the axial linear electron path, which direction is vertical in Fig. 1. As a result of this angular relationship, expansion or contraction of electrode 14, due to temperature changes thereof, will cause corresponding downward or upward movement of the center of said electrode or apex of the cone, thereby correspondingly decreasing or increasing the distance a between the electrode elements 13 and 14 and correspondingly increasing or decreasing the capacitance between electrode elements 13 and 14 to thereby change the resonant frequency of resonator 2.

The cavity resonator 2 is connected, by means of a lead 19, to the positive terminal of a battery 12, the negative terminal of which is connected to cathode lead 5, so that said resonator has a positive potential with respect to cathode 6.

The electrodes 13 and 14, which are connected to each other by the cavity resonator 2, constitute an electron velocity-modulating electrode structure.

A metallic repeller electrode 20 is positioned on the opposite side of the electrode structure 2, 13, 14 from cathode 6; electrode 20 may be supported, for example, at the end of a stiff lead-in conductor 21 integral with said electrode and sealed through the upper end of envelope portion 3. Electrode 20 may be circular, for example, having its center on the longitudinal axis of tube 1, the diameter of said electrode being somewhat larger than the diameter of the axial openings in electrodes 13 and 14 but smaller than the diameter of electrode 14. An annular metallic member 22, of substantially inverted L-shape in cross-section, is secured to electrode 20, adjacent the lower end thereof, to provide an annular chamber 23 which surrounds the bottom or active end of repeller electrode 20. A hollow substantially toroidal cathode 24 is positioned in chamber 23, with the lower surface of said cathode located somewhat above the lower end wall of member 22, and the lower end wall of the repeller electrode 20 proper, as shown. The lower surface of cathode 24 is covered with an electron-emissive coating, as indicated.

Cathode 24 is supported in position by a pair of ceramic eyelets 25 which are diametrically opposite each other and are each cemented or otherwise secured to the upper wall of said cathode. These eyelets pass through suitable metallic bushings 26 which secure said eyelets to the horizontal portion of member 22. A toroidal heater coil 27, one end of which is secured to cathode 24, is located inside said cathode to heat the same to the temperature of thermionic emission.

A lead-in conductor 28 is connected, at its inner end, to the cathode 24, and passes upwardly through one of the insulating eyelets 25 and out through a suitable seal in the upper end of envelope portion 3. A lead-in conductor 29 is connected, at its inner end, to the free end of heater

coil 27, and passes upwardly through the opposite eyelet 25 and out through a suitable seal in the upper end of envelope portion 3. Lead-ins 28 and 29 may help to support cathode 24 and heater 27 in position, along with eyelets 25.

Cathode 24 is mounted adjacent electrode 20, in such a position as to project electrons downwardly onto electrode 14 or to cause electrons to impinge on said electrode, since the diameter of electrode 20 is smaller than that of electrode 14 and since cathode 24 immediately surrounds electrode 20.

Lead-in 21 of repeller 20 is connected to the negative terminal of a potential source 30, the positive terminal of which is connected to cathode lead 5, so that said repeller has a negative potential with respect to the cathode 6 of the electron gun. A source 31 of heating current has its opposite terminals connected to leads 28 and 29, to supply heating current to heater 27.

The annular chamber 23 houses the cathode 24; walls defining this chamber are electrically connected to the repeller 20, so that electrically, as well as physically, a portion of electrode 20 partially surrounds said cathode. A source of bias potential 32 has its negative terminal connected to repeller lead 21, and a movable tap 33 on said source is connected to cathode lead 28, so that, in effect, a potential negative with respect to cathode 24 is applied to repeller 20; the amount of this negative bias can be varied by movement of tap 33. The walls defining chamber 23 serve as a grid, to control the flow of electrons between cathode 24 and electrode 14, the flow depending on the voltage applied, from source 32, between cathode 24 and electrode 20.

When the tube 1 is energized by potentials, as above described, from sources 8, 12, and 30, a beam of electrons coming from the cathode 6 will be accelerated by the accelerating electrode 9, and pass through the electrodes 13 and 14 of cavity resonator 2. As the beam emerges from the electrode 14, it is reflected by the repeller electrode 20 back through the pair of electrode elements 13 and 14. As is well known, the initial passage of the beam through the electrodes 13 and 14 produces a bunching action, and, upon reflection and repassage of the beam through these electrodes, a debunching action results, which feeds ultra-high-frequency energy to the resonant circuit formed by the cavity resonator 2, thus setting up ultra-high-frequency oscillations, of a frequency determined by the relative dimensions of said resonator; which may be abstracted by waveguide 16.

By changing the spacing between elements 13 and 14, that is, by changing the gap length a , the resonant frequency of resonator 2 may be varied; in other words, by so doing, the tube 1 may be tuned. When heater 27 is energized from source 31, cathode 24 emits electrons. There is normally a high potential between cathode 24 and electrode 14 of the cavity resonator, said electrode being positive with respect to said cathode; this can be seen from the fact that repeller 20 is negative with respect to cathode 6 and cavity resonator 2 is highly positive with respect to said cathode, while cathode 24 is only slightly positive with respect to repeller 20. Electrons from cathode 24 therefore strike electrode 14 with sufficient energy and in sufficient numbers to raise its temperature; the electron flow between cathode 24 and electrode 14 is controllable, thereby also controlling the temperature of said electrode, by varying the potential applied between

said cathode and repeller electrode 20. The temperature of electrode 14 is increased in proportion to the number and energy of the electrons impinging upon it.

As the temperature of electrode 14 increases, it expands a substantial amount, due to its substantial thermal coefficient of expansion; this expansion produces a downward movement at the apex of the cone, due to the angular relation of said electrode and the electron path, as explained above. The downward movement decreases the gap spacing or length a , increasing the capacitance provided by said gap and lowering the resonant frequency of resonator 2, thus lowering the oscillatory frequency of the klystron 1.

When fewer electrons, or electrons of lower energy content, impinge on electrode 14, the temperature of said electrode drops, causing shrinkage thereof, increasing gap length a and raising the frequency of the oscillations.

The electron flow between cathode 24 and electrode 14 is controllable by controlling the potential applied between said cathode and electrode 20 by moving the tap 33 on source 32; thus, by controlling this potential, the temperature of electrode 14, and therefore also the frequency of klystron 1, may be controlled.

The entire upper portion 2c of cavity resonator 2, except for electrode 14, is made of relatively thick copper which is brazed to the copper portion 2b of the resonator. Since electrode 14 has low heat conductivity, and, since this copper portion has high heat conductivity, there is relatively small temperature variation of resonator section 2c as electrode 14 is varied in temperature.

From all of the above, it will be seen that I have devised a novel, thermal, means for controllably tuning a cavity resonator. It has been found that, with this invention, frequency changes of a klystron may be effectuated in time intervals on the order of a half-second or less, since the electrons act directly on electrode 14 of the cavity resonator, and not through any linkage mechanism.

Cavity resonator 2 is hermetically sealed, and the entire interior of said resonator is evacuated. Upper glass envelope 3 may be sealed to an annular wall 34 projecting upwardly from the upper exterior surface of resonator 2, while lower glass envelope 4 may be sealed to a similar annular wall 35 projecting downwardly from the lower exterior surface of said resonator. Therefore, cavity resonator 2 and envelopes 3 and 4 provide an evacuated enclosure.

Now referring to Fig. 2, a modification is shown by means of which the upper cathode may be omitted. In this figure, similar reference numerals are used to refer to parts the same as those of Fig. 1.

Repeller electrode 36 has a longitudinal axial aperture 37 extending entirely therethrough, and supported in this aperture, but insulated from electrode 36 by means of a vitreous disk 38 near the lower end of said aperture, is a rod-like electrode member 39. Electrode 36 and member 39 both pass out of the evacuated enclosure, being sealed through the top wall of upper envelope portion 3.

The positive terminal of a bias potential source 40 is connected to repeller electrode 36, and a movable tap 41 on said source is connected to member 39, so that a potential, negative with respect to repeller 36, is applied to said member; the value of this negative potential can be varied by movement of tap 41.

In the device of Fig. 2, it has been found that the electron stream from the regular klystron gun 6, 9 can be area-modulated in the repeller zone by a potential applied between repeller 36 and member 39. In other words, the cross-section of the stream, on its return trip from the repeller zone back through electrodes 13 and 14, can be varied by varying the potential between member 39 and repeller 36. It has been found that the electron stream will be spread more as the member 39 is made more negative, and that the potential of said member will determine the amount of spread of the stream. As the stream is spread, some of the electrons therein will impinge on electrode 14, the number of electrons so impinging depending on the amount of spreading of the stream, and therefore on the potential applied to member 39.

The electrons which impinge on electrode 14 will do so with sufficient velocity and in sufficient numbers to raise the temperature of said electrode, thus producing a thermal tuning action as in Fig. 1. The action may be controlled by controlling the potential applied to member 39, in this manner controlling the temperature of electrode 14 by controlling the electron flow impinging thereon, thereby also controlling the frequency of klystron 1 accordingly.

Of course, it is to be understood that this invention is not limited to the particular details as described above, as many equivalents will suggest themselves to those skilled in the art. For example, instead of depressing the central portion of electrode 14 so that the apex of the cone points downwardly, the central portion of said electrode may be raised, in which case a frequency variation with electron flow opposite to that described above would be effectuated. Various other variations will suggest themselves. It is accordingly desired that the appended claims be given a broad interpretation commensurate with the scope of this invention within the art.

What is claimed is:

1. An electron velocity-modulation discharge tube, comprising a plurality of electrodes including an electron-emissive cathode, an electron velocity-modulating electrode structure comprising a pair of spaced electrode elements through which an electron path from said cathode passes, said electrode elements being connected to each other by and forming part of the walls of a cavity resonator, one of said electrode elements being thermally deformable to produce variations in the distance between said electrode elements in response to variations in the temperature of the same, and controllable means adjacent said elements for varying the temperature of said one electrode element to vary said distance, said controllable means comprising electron directing electrode means adjacent said elements for causing electrons to impinge on said deformable element.

2. An electron velocity-modulation discharge tube, comprising a plurality of electrodes including an electron-emissive cathode, an electron velocity-modulating electrode structure comprising a pair of spaced electrode elements between and through which a linear electron path from said cathode passes, a portion of one of said electrode elements forming an angle with the direction of said path, said angle being different from ninety degrees, whereby variations in the temperature of said portion will produce variations in the length of the portion of said path between said electrode elements, said electrode

elements being connected to each other by and forming part of the walls of a cavity resonator, and electron directing electrode means adjacent said elements for causing electrons to impinge upon said portion for varying the temperature of said portion of said one electrode element.

3. An electron velocity-modulation discharge tube, comprising a plurality of electrodes including an electron-emissive cathode, an electron velocity-modulating electrode structure comprising a pair of spaced electrode elements between and through which a linear electron path from said cathode passes, a portion of one of said electrode elements forming an angle with the direction of said path, said angle being different from ninety degrees, said portion having an appreciable thermal coefficient of expansion whereby variations in the temperature of said portion will produce substantial variations in the length of the portion of said path between said electrode elements, said electrode elements being connected to each other by and forming part of the walls of a cavity resonator, and controllable electron directing electrode means adjacent said elements for causing electrons to impinge upon said portion for varying the temperature of said portion of said one electrode element.

4. An electron velocity-modulation discharge tube, comprising a plurality of electrodes including an electron-emissive cathode, an electron velocity-modulating electrode structure comprising a pair of spaced electrode elements between and through which a linear electron path from said cathode passes, at least a portion of one of said electrode elements forming an angle with the direction of said path, said angle being different from ninety degrees, whereby variations in the temperature of said portion will produce variations in the length of the portion of said path between said electrode elements, said electrode elements being connected to each other by a cavity resonator having a resonant frequency dependent on the length of said portion of said path, an additional electrode on the opposite side of said electrode structure from said cathode and a second electron-emissive cathode mounted adjacent said additional electrode to project electrons onto said portion of said one electrode element, means adjacent said portion for causing impingement of said electrons on said portion of said one electrode element with sufficient velocity to raise the temperature thereof, a portion of said additional electrode partially surrounding said second cathode for controlling the electron flow between said second cathode and said portion of said one electrode element, by the control of the voltage applied between said second cathode and said additional electrode.

5. An electron velocity-modulation discharge tube, comprising a plurality of electrodes including an electron-emissive cathode, an electron velocity-modulating electrode structure comprising a pair of spaced electrode elements between and through which a linear electron path from said cathode passes, at least a portion of one of said electrode elements forming an angle with the direction of said path, said angle being different from ninety degrees, said portion having a substantial thermal coefficient of expansion whereby variations in the temperature of said portion will produce substantial variations in the length of the portion of said path between said electrode elements, said electrode elements being connected to each other by a cavity resonator having a resonant frequency dependent on the

length of said portion of said path, an additional electrode on the opposite side of said electrode structure from said cathode, and a second electron-emissive cathode mounted adjacent said additional electrode to project electrons onto said portion of said one electrode element, means adjacent said portion for causing impingement of said electrons on said portion of said one electrode element with sufficient velocity to raise the temperature thereof, a portion of said additional electrode partially surrounding said second cathode for controlling the electron flow between said second cathode and said portion of said one electrode element, by the control of the voltage applied between said cathode and said additional electrode.

6. An electron velocity-modulation discharge tube, comprising a plurality of electrodes including an electron-emissive cathode, an electron velocity-modulating electrode structure comprising a pair of spaced electrode elements between and through which a linear electron path from said cathode passes, the portion of one of said electrode elements adjacent said path forming an angle with the direction of said path, said angle being different from ninety degrees, whereby variations in the temperature of said portion will produce variations in the length of the portion of said path between said electrode elements, said electrode elements being connected to each other by and forming part of the walls of a cavity resonator, an additional electrode on the opposite side of said electrode structure from said cathode and adapted to reflect the electron stream from said cathode back through said electrode structure, and an electron directing electrode adjacent said additional electrode.

7. An electron velocity-modulated discharge tube, comprising a plurality of electrodes including an electron-emissive cathode, an electron velocity-modulating electrode structure comprising a pair of spaced electrode elements between and through which a linear electron path from said cathode passes, the portion of one of said electrode elements adjacent said path forming an angle with the direction of said path, said angle being different from ninety degrees, said portion having an appreciable thermal coefficient of expansion whereby variations in the temperature of said portion will produce substantial variations in the length of the portion of said path between said electrode elements, said electrode elements being connected to each other by and forming part of the walls of a cavity resonator, an additional electrode on the opposite side of said electrode structure from said cathode and adapted to reflect the electron stream from said cathode back through said electrode structure, and an electron directing electrode adjacent said additional electrode for spreading said stream whereby some of the electrons therein impinge on said portion of said one electrode element with sufficient velocity to raise the temperature thereof.

8. An electron velocity-modulation discharge tube, comprising a plurality of electrodes including an electron-emissive cathode, an electron velocity-modulating electrode structure comprising a pair of spaced electrode elements through which an electron path from said cathode passes, said electrode elements being connected to each other by and forming part of the walls of a cavity resonator, one of said electrode elements being thermally deformable and frustro-conical to produce variations in the distance between said elec-

trode elements in response to variations in the temperature of the same, and controllable means adjacent said elements for varying the temperature of said one electrode element to vary said distance, said controllable means comprising electron directing electrode means adjacent said elements for causing electrons to impinge on said deformable element.
